UNITED STATES PATENT OFFICE.

FRANK W. BURPEE, OF BELLINGHAM, WASHINGTON.

CUTTING AND DIEING DEVICE.

1,084,784.

Specification of Letters Patent.

Patented Jan. 20, 1914.

Original application filed November 13, 1911, Serial No. 660,156. Divided and this application filed June 19, 1912. Serial No. 704,678.

To all whom it may concern:

Be it known that I, FRANK W. BURPEE, a citizen of the Dominion of Canada, and a resident of the city of Bellingham, in the 5 county of Whatcom and State of Washington, have invented certain new and useful Improvements in Cutting and Dieing Devices, of which the following is a specification, this being a division of my application, 10 Serial No. 660,156, filed November 13, 1911.

My invention relates to devices of the above type and has for its primary object the provision of a construction which is primarily devised for forming heads or closures 15 for receptacle bodies.

A further object resides in the provisions of such a construction wherein the heads or closures as formed are suitably apertured.

With the above and other objects in view, 20 to be referred to as my description progresses, the invention resides in the features of construction, arrangements and combinations of parts hereinafter described and succinctly defined in my annexed claims.

25 Referring to the accompanying drawing, illustrating a practical embodiment of my invention and wherein like characters of reference indicate like parts throughout; Figure 1 is an end elevation of the apparatus. 30 Fig. 2 is a fragmentary longitudinal section illustrating the dies in operation. Fig. 3 is a similar view with the dies open. Fig. 4 is a fragmentary section of the female die, on a large scale. Fig. 5 is a fragmentary 35 section of the male die, and Fig. 6 is a top plan of the mechanism.

Reference numerals 14 and 15 indicate hollow cutting and forming dies, the former or male die of which is carried by a reciprocating slide 16, guided in lugs 10 of an upright 40 12 of the main frame 13, while die 15 is fixed to an extension 17 of said upright.

Reference numeral 11 indicates a chute arranged between and below dies 14 and 15 45 and fixed as by a screw bolt 11' to extension 17.

Die 15 is provided with a cutting edge 15' and an internal annular forming section 15'', the latter being spaced inwardly from 50 the former to permit of the entrance there-between of die 14, which latter flares slightly at its end to its outer or cutting edge to thereby first coat with cutting edge 15' to cut out the blank, as A, and then during further advance movement to bend the edge 55

portion of such blank over the adjacent end of forming section 15''.

Reference numeral 19 indicates a yieldingly held presser consisting of a ring encircling an internal auxiliary cutting die 18 60 of die 14, the same during advance movement of said die 14 pressing and firmly holding the blank against the end of forming section 15'', which end is grooved, as shown more clearly in Fig. 4, to provide a cutting edge 65 15^a at the edge of the bore of said forming section. Subsequently to this operation of the presser, die 18 moves into die forming section 15'' and, coacting with the inner or cutting edge 15^a thereof, cuts the usual outlet opening in the formed blank which is to serve as the top wall of the receptacle. 70

Reference numeral 26 indicates a tube communicating with the bore of die 15 for conducting the waste center cuttings from 75 the blank to a suitable point of discharge.

An ejector 20 is slidably mounted in die 15 on the forming section 15'' thereof, the same being provided with rearwardly extending stems 21 which project to the rear 80 of the die for movement into the path of a positive actuator 23, slidably mounted on tube 26. Springs 22 are also preferably engaged with stems 21 to project the ejector 20, these acting quickly upon withdrawal of 85 die 14, but as such yielding means is not at all times as certain in its action as might be desired, I provide the positive actuator 23, which being connected by rods 24 to pins 25 of slide 16 to reciprocate with die 14, will in 90 the event of springs 22 failing to perform their function strike stems 21 and thereby operate the ejector.

Reference numeral 30 indicates a drive shaft provided with an eccentric 31 with 95 which a strap 32 is engaged. Connected with strap 32 by a driving rod 33 is an operating lever 34 for slide 16, said lever being fulcrumed at 34' and having its upper end portion bifurcated and pivotally connected with slide pins 25.

Reference numeral 40 indicates a strip of paper from which the blanks are cut. This is preferably of considerable length, and in my said application Serial No. 660,156, filed 105 November 13, 1911, of which this is a division, the same is wound on a spool and fed downwardly following opening of the dies. The manner of feeding paper or the type of paper fed is immaterial. When however, a 110

strip of paper is employed to have the blanks cut therefrom, I employ a movable guide 41, this being connected with rods 42, slidably engaged with lever 34 and having 5 a yielding driving connection therewith through the medium of springs 43, for movement of its upper end portion in common with slide 16, which last named end portion of guide 41 is suitably apertured, as 10 at *a*, to permit of its clearing die 15 for proper coaction of the latter with die 14, which following forward movement of said guide engages the strip of paper and presses the same against die 15 to effect the cutting 15 of the blank, as hereinbefore set forth. Guide 41 is secured at its lower end portion, as at 41', to standard 12 and has its upper end portion lying at the forward side of the strip of paper 40 so as to be capable of moving the latter clear of the path of travel of the formed closure to chute 11.

In operation, power is applied to shaft 30, as by a belt, not shown, taking over a pulley 50 to thereby oscillate lever 34, during advance movement of which the blank is cut and formed and during retractive movement of which the formed blank is ejected by ejector 20 into chute 11.

Having thus described my invention what 30 I claim as new, and desire to secure by Letters Patent of the United States of America, is:—

1. In a machine of the character described, a male forming die, a female forming die, means for reciprocating one of said dies, a yielding held ejector for removing the formed article from said female die, and a positive actuator for said ejector operated by and during movement of said movable die.

2. In a machine of the character de-

scribed, a die provided with outer and inner continuous cutting edges spaced one from the other, said die being further provided with a forming section intermediate its 45 cutting edges, a second die provided with a cutting edge for coaction with the outer cutting edge of said first-named die and with a forming section for bending a blank over the forming section of said first-named die, 50 an internal cutting section to said last-named die lying inwardly and rearwardly of said first-named cutting edge thereof for coaction with the inner cutting edge of said first-named die, and means for reciprocating 55 one of said dies toward and from the other.

3. In a machine of the character described, a die provided with a cutting edge and an internal hollow forming section spaced from said cutting edge and provided 60 at the edge of its bore with a cutting edge, a second die provided with a cutting edge for coaction with the cutting edge of said first die, said second die being provided with a hollow forming section flaring outwardly 65 toward its said cutting edge for bending a blank over the forming section of said first die, means in said second die for yieldingly pressing the blank against the forming section of said first die, an internal cutting edge to said second die lying inwardly and rearwardly of said first-named cutting edge thereof for cutting against the inner cutting 70 edge of said first-named die, and means for reciprocating one of said dies.

Signed at Bellingham, Wash. this 10 day of June 1912.

FRANK W. BURPEE.
